SNAP-ACTION DEVICES

David Alexander Wilson, Sunderland, England, assignor to Burgess Products Company Limited, Hinckley, England, a company of Great Britain and Northern Ireland

Filed Sept. 3, 1958, Ser. No. 758,825

Claims priority, application Great Britain Sept. 30, 1957
3 Claims. (Cl. 200—67)

This invention relates to snap-action devices and more particularly to snap-action electric switches, including switches having rotary operating members, which are suitable for use in coin-operated devices.

The invention has for an object to provide a snap-action device of simple construction which has a long life, and which more particularly is operable by a very low rotary torque.

A snap-action device according to the invention comprises two spaced fixed stops, a substantially flat, rigid member having one end disposed between said stops and its other end pivotally engaged at a fixed abutment, a tension link including or comprising a coil spring anchored at one end to said flat member remotely from said abutment, and at its other end to a fixed anchorage, a rotary operating cam or eccentric disposed to bear on one side of said tension link, and a unitary element affording said fixed abutment and fixed anchorage and at least one bearing for a spindle of said cam or eccentric.

Preferably, the flat member is U-shaped or forked, with two parallel arms pivotally bearing by their ends in a common line on a pair of fixed abutments, and a single tension link having one end anchored at the root of the fork extends between said arms.

The arrangement is such that when the cam or eccentric does not bear upon the tension spring, the latter pulls the free end of the flat member into engagement with one of the fixed stops, the points of anchorage of the tension link and the line of said pivotal abutment or abutments being in a triangle having a large obtuse angle (nearly 180°) at said line, in a plane normal to said line. When the cam or eccentric is caused to bear upon the tension link, the latter is flexed and the axis of the portion of the link extending from the radius through the point of contact of the cam or eccentric with the link to the anchorage on the flat member is caused to pass through a common plane including said last mentioned anchorage and said pivotal line, to form another shallow triangle, inverted with respect to the first, and again having a large obtuse angle at said pivotal line. During such displacement, the free end of the flat member is caused to move with a snap-action from engagement with one of said fixed stops to engagement with the other. When the operating torque applied to the cam or eccentric is reduced, the tension of the extended, flexed spring serves to restore the switch to its initial state, turning the cam or eccentric back and causing the free end of the flat member to move back with a snap-action between the fixed stops.

Said flat member may carry at its free end either a single electrical contact, one of said fixed stops also being an electrical contact, so that the device forms a snap-action make-and-break switch, or said member may carry an opposed pair of contacts, each fixed stop being an electrical contact, so that the device forms a snap-action change-over switch, the element affording the abutment for said flat member serving in each case as a terminal of the switch.

A snap-action device or switch mechanism as aforesaid may be mounted on a base, for example a plastic moulding, having a substantially flat surface with respect to which said pivotal abutment line is perpendicular and the

2

tension link lies parallel. Such a base may provide one bearing for the spindle of the cam or eccentric, or said unitary element may include a portion adjacent said surface of the base providing one such bearing and another, spaced parallel portion affording a second bearing.

Said unitary element may be a pressing of sheet metal, for example, of brass or a like alloy.

An embodiment of a switch including a snap-action mechanism according to the invention and a modification will be described by way of example with reference to the accompanying drawings, all on an enlarged scale, wherein

FIG. 1 is a front view of the switch with a cover mainly broken away to show the internal construction,

FIG. 2 is a section on the line A—A of FIG. 1.

FIG. 3 is a view of a detail, seen in the direction of arrow B in FIG. 1,

FIG. 4 is a plan view of said detail,

FIG. 5 is a view of a flat blank from which said detail is formed, and

FIG. 6 is a view corresponding to FIG. 1, partly in section, of a modification.

The embodiment of the invention comprises the combination of a snap-action mechanism, mounting means for said mechanism and three terminals (common, normal open and normal closed) in a change-over switch.

The switch 1 has an insulating base 2 with parallel flat surfaces at three levels which for convenience of description will be considered as being in vertical planes. The basic surface level may be considered as that of a middle portion 3 and a marginal shoulder 4, from which project a three-sided rib 5 and two small lozenges 6 and 7 serving jointly to locate by their outer edges the rim 8 of a box-like cover 9. Through diagonally opposed corners of the cover and the base are formed holes 10 by which said elements are secured together, as shown by tubular rivets 11.

There are also two depressions 12 and 13. The former serves to accommodate and locate by their upper right-hand corners and adjacent top and side edges vertical tab portions 14 and 15 (which serve respectively as the common and normal open terminals of the switch) of the aforesaid unitary element 16 and of another element 17. The depression 13 serves to accommodate and locate a vertical tab portion 18 (which serves as the normal closed terminal of the switch) of a third element 19. Each of these elements is secured by a rivet 20.

The unitary element is a pressing of sheet brass, preferably silver plated, made from a blank as shown in FIG. 5, by bending to the form shown in FIGS. 1—4 on the lines a—a, b—b and c—c. The tab 14 has at or adjacent its upper end a perpendicularly projecting arm 21 in a vertical plane with two spaced parallel upward extensions 22 having each one of two aligned, horizontal grooves 23 to serve as pivotal abutments. The tab also has another perpendicularly extending arm 24, lying in a horizontal plane which passes close to said grooves, and having in its side remote from said upward extensions a notch 25 to provide an anchorage for one end of a tension link constituted in this embodiment solely by a coil spring 26 (FIG. 1).

The element also includes, between said upward extensions and said notched arm, an upwardly extending tongue 27, in a plane parallel to that of the tab 14, which has a hole 28 to serve as a bearing for one end of a cam spindle, or preferably, as shown, an element of a cam and spindle assembly. This hole is shown aligned with a hole 29 in a bush or housing 30 secured in the base. In the preferred arrangement, as illustrated, said notched arm 24 is an integral part of an L-shaped prolongation 31 of the outer of said upward extensions 22, but down into a

horizontal plane and having bent up from the middle of the outer edge of its shank, and integral therewith, the aforesaid bearing tongue 27. This arrangement has the effect that stress in the tension spring 26, which tends to pull said notched arm towards said upward extensions, is resisted by the shank of the L-shaped prolongation lying alongside the spring.

A substantially flat member 32, having two parallel arms, is located substantially horizontally and held with the oblique bent ends 33 of the arms in engagement with the aforesaid abutment grooves 23 by the spring 26, extending between said arms and having one end 34 anchored to the flat member 32 at its crotch and the other end 35 anchored in said notch 25. The bent ends 33 of the member 32 engage, as shown in FIG. 1, in the grooves 23 with an edge contact. The tip of the member 32 carries two electrical contacts 36, one on each side, and is located between a pair of fixed contacts, one contact 37 being constituted by a horizontal extension parallel to the base from and integral with the element 17, and the other contact 38 by a horizontal extension, perpendicular to the base, from the element 19.

Mounted on a spindle 39, which is partly supported for angular displacement in the bush 30 secured in the base and extends perpendicularly to the base, is an eccentric cam 40 of insulating material which receives one end of the spindle and is supported rotatably in the hole 28 in the tab 27. The cam is turnable with the spindle, and is adapted to bear when turned on the upper side of the tension coil spring 26 so as to deflect it and cause operation of the switch.

In the modification shown in FIG. 6 the tension link comprises a shorter coil spring 46, in alignment with a wire link 47. Said link has two downwardly hooked ends 48 and 49, the former engaging a hooked end 50 of the spring and the latter being anchored in the notch 25. The other hooked end 51 of the spring is anchored to the flat member 32 of its notch. The cam 40 bears on the wire link 47 as shown. This arrangement has the effect of affording a significant improvement in mechanical life of the mechanism, even as compared with that afforded by the arrangement wherein the cam bears on the side of a longer coil spring as shown in FIG. 1.

On the outer side of the base the spindle has a boss 41 whereby it may be turned. Said boss may have attached to it means adapted for displacement by a cam or a coin-operated mechanism in a pre-payment device. As described above, the inherent restoring force of the tension coil spring, when extended by flexing in either of the arrangements illustrated, enables the mechanism after being operated by a unidirectional force to return to its initial state on reduction of said force.

For limiting the angular displacement of the cam there is mounted on the spindle 39 a disc 42 with a radial extension the end 43 of which is bent to form an axial flange which is displaceable between abutments presented by the inner edge of the upper part of the rib 5 and the inner edge of an arm 44 formed to extend inwardly from the side of said rib in the base moulding.

The cam 40 and its spindle 39 may alternatively be a unitary moulding for example of nylon plastic. The base may be a moulding of a suitable, e.g., phenolic, plastic.

There may be associated with the boss 42 a wire operating arm formed at one end as a torsion spring with a tail which intersects the axial plane of said arm, such that said torsion spring may be opened for location on or removal from the spindle by pressing the arm and the tail together, whereby the arm may be located on the spindle in any desired or convenient angular relationship with the cam. Said operating arm may be lodged in a transverse slot 45 in the end of the boss.

What I claim and desire to secure by Letters Patent is:

1. In a snap-action switch comprising two spaced fixed stops of which at least one is an electrical contact, a substantially flat rigid member having one end disposed between said fixed stops, a fixed abutment which is engaged by the other end of said rigid member, at least one contact carried by said one end of said rigid member to be engageable with said fixed contact, a link resiliently extensible under tension anchored at one end to said rigid member remotely from said abutment, a fixed anchorage to which the other end of said tension link is anchored, a rotary operating cam disposed to bear on one side of said tension link, and a spindle with which said cam is assembled, the combination of a snap-action mechanism separable from the switch in sub-assembly, comprising said rigid member and said tension link with a unitary element affording said fixed abutment for said rigid member, said fixed anchorage for said tension link, and at least one bearing for said cam-and-spindle assembly.

2. In a snap-action switch, a snap-action mechanism as claimed in claim 1, in which said unitary element comprises a metal sheet bent along three fold lines to form four flat members, of which a first one serves as a mounting plate and common terminal for said mechanism in the switch, a second one accommodates said fixed abutment, a third one accommodates said fixed anchorage, and the fourth one accommodates said bearing.

3. In a switch, a snap-action mechanism as claimed in claim 1, in which said tension link comprises a coil spring anchored at one of its ends to said rigid member remotely from said abutment, and a wire link element having two hooked ends anchored by one of said ends to the other end of said coil spring and by the other of said ends to said fixed anchorage, said cam and said wire link being disposed so that said cam bears on one side of said wire link.
